UNITED STATES PATENT OFFICE.

CARL SZAMEITAT, OF HAMBURG, GERMANY.

SADDLE ADJUSTING ITSELF AUTOMATICALLY IN TWO DIRECTIONS.

No. 821,135.

Specification of Letters Patent.

Patented May 22, 1906.

Application filed September 3, 1904. Serial No. 223,993.

To all whom it may concern:

Be it known that I, CARL SZAMEITAT, a subject of the German Emperor, residing at 95 Steinstrasse, Hamburg, in the German Empire, have invented certain new and useful Improvements in a Saddle Adjusting Itself Automatically in Two Directions, of which the following is a specification.

My invention relates to an improved construction for riding-saddles of that class wherein the supporting surfaces or parts are adapted to yield to conform to the contour of the animal.

To this end my invention consists of a fork and downwardly-extending hinged stays connected with the fork by springs in a manner to maintain the stays tightly in engagement with the sides of the animal. Said stays are connected with the saddle-tree, and there are provided longitudinally-disposed springs which are also connected with the saddle-tree at a point near the cantle and with said stays.

My invention will be more fully described in connection with the accompanying drawings, in which—

Figure 1 is a perspective view of a gentleman's saddle embodying the main features of my invention. Fig. 2 is a like view of a lady's saddle. Fig. 3 illustrates a modified embodiment of my invention.

The saddle-tree is shown without the usual padding and consists of back straps *a*, which terminate at the rear in a cantle *a'* and extend forwardly to a point approximately at the horn or pommel. The fork *b*, by which the pommel or horn may be formed, is provided with downwardly-extending stays *c c'*, hinged to the fork at *d d'*. Springs *f* are provided for normally holding the stays *c* in contact with the sides of the animal, the said springs being rigidly secured to the inner faces of the fork at *f'* and slidably connected with the stays by means of a slot-and-pin connection *f''* and *g*. The forward ends of the back straps *a* are secured to the stays *c c'* at a

point adjacent the hinged connection of the same with the fork *b*. Longitudinally-disposed springs *i i* are provided which extend from the stays *c c'*, to which they are pivotally secured rearwardly to a point adjacent 50 the cantle, where they are secured at *h* to the saddle-tree. *e* is a buckle to which the stirrup-strap may be attached.

In the form shown in Fig. 3 the saddle-tree is composed of a fork *j* and pommel *k*, which are pivotally secured to back plates or bars *l*. Said parts *j* and *k* are also connected by a strap *m*, provided with lacings *n*, connecting said strap with the bars *l*. The longitudinally-disposed springs *i* are secured to 55 the lower faces of the back bars *l* and perform their function in a manner similar to springs shown in the preferred forms of Figs. 1 and 2.

In my improved form of saddle the animal bearing or supporting parts are not only adapted to yield, but are so constructed as to conform with all irregularities of the contour of the surface with which they engage. Furthermore, it will be noted that by reason of 70 the fact that the parts *a a'* of the saddle-tree are integral from the cantle to the stays *c c'* a very rigid support or seat is provided, as the hinged or movable parts are all at the forward end of the saddle.

What I claim, and desire to secure by Letters Patent, is—

A saddle-tree comprising a fork, stays hinged thereto, a cantle, back plates connecting said cantle and stays, springs connecting 80 said stays and fork, and longitudinally-disposed springs secured to said stays and the rear of said saddle.

In testimony whereof I affix my signature in presence of two witnesses.

CARL SZAMEITAT.
